DESIGN FOR A DISPLAY DEVICE

Oliver Gifford Crich, London, Ontario, Canada,
assignor to Somerville Paper Boxes Limited,
London, Ontario, Canada

Application April 19, 1934, Serial No. 51,446

Term of patent 7 years

To all whom it may concern:

Be it known that I, OLIVER GIFFORD CRICH, a subject of the King of Great Britain, residing at the city of London, in the county of Middlesex, Province of Ontario, Canada, have invented a new, original, and ornamental Design for a Display Device of which the following is a specification, reference being had to the accompanying drawings, forming part thereof.

Figure 1 is a front view of the display device showing my new design a portion of the top being broken away for convenience of illustration;

The said display device comprises a backwardly inclined, upwardly projecting back piece and an outwardly inclined front piece shaped and formed as an egg carton.

I claim:

The ornamental design for a display device as shown and described.

OLIVER GIFFORD CRICH.
